A. W. BRACKIN.
KEROSENE ATTACHMENT FOR GASOLINE ENGINES.
APPLICATION FILED JULY 31, 1916.

1,224,441.

Patented May 1, 1917.

UNITED STATES PATENT OFFICE.

ARTHUR WARREN BRACKIN, OF LETOHATCHIE, ALABAMA.

KEROSENE ATTACHMENT FOR GASOLENE-ENGINES.

1,224,441.

Specification of Letters Patent.

Patented May 1, 1917.

Application filed July 31, 1916. Serial No. 112,241.

To all whom it may concern:

Be it known that I, ARTHUR WARREN BRACKIN, a citizen of the United States, residing at Letohatchie, in the county of 5 Lowndes and State of Alabama, have invented or discovered certain new and useful Improvements in Kerosene Attachments for Gasolene-Engines, of which the following is a specification, reference being had therein 10 to the accompanying drawings.

This invention has for its object the provision of a simple and inexpensive attachment, readily applicable to any existing water-cooled internal combustion engine, 15 whereby said engine may be efficiently operated by kerosene, as a fuel, in substitution for the usual gasoline.

The more particular objects of the invention, together with means whereby the same 20 may be carried into effect, will best be understood from the following description of one form or embodiment thereof illustrated in the accompanying drawings. It will, however, be understood that the particular 25 construction and arrangement described and shown have been chosen for illustrative purposes merely, and that the invention, as defined by the claims hereunto appended, may be otherwise practised without departure 30 from the spirit and scope thereof.

In said drawings:

Figure 1 is side elevation, partly in section, of an internal combustion engine equipped with the invention, showing the 35 parts in position for normal running.

Fig. 2 is a section on the line 2—2, Fig. 1.

Fig. 3 is a detail sectional view of the casing and two-way valve illustrated in Fig. 1, showing said valve in the position to start 40 the engine.

The internal combustion engine herein shown comprises a working cylinder 10 containing a piston 11 and inclosed by a water jacket 12 forming a part of the cooling system of the engine. Communicating with the cylinder 10 through the usual inlet valve (not shown) is an intake 13 leading from a charge forming device comprising a fuel supply cup 14, fuel nozzle 15 controlled by 45 a needle valve 16, air intake 17, and fuel supply and overflow pipes 18 and 19, the former leading from the regular fuel tank (not shown). The engine parts thus far described may be of any usual or well known form familiar to those skilled in the art and, 50 specifically, form no portion of the present

invention, the essential features of which will now be explained.

20 denotes a casing provided with a threaded nipple 21 which, when the attachment is applied, is received in a tapped opening drilled for that purpose in the wall of the intake 13, whereby said casing is attached to said intake. If found necessary or desirable said casing may be further secured in place by suitable screws or bolts 22, or otherwise. Within the nipple 21 is a bore or passage 23 extending through an injector or nozzle 24 in which said nipple terminates, communicating with the interior of 70 the intake 13, and controlled by a needle valve 25. At its opposite end the passage 23 terminates in a port in the wall of a valve chamber containing a two-way valve 26, said valve chamber having other ports 75 communicating with passages 27 and 28 leading to threaded sockets 29 and 30, respectively, formed on the exterior of the casing 20. The two-way valve 26 is provided with a port or passage adapted to 80 place the passages 27 and 28 alternatively into communication with the passage 23 when said valve is turned by any suitable means, herein shown as an arm 31 and rod 32. Connected to the socket 29 is a pipe 33 85 leading from a small auxiliary fuel tank or reservoir 34. To the socket 30 is connected a pipe 35 terminating in a threaded nipple 36 which, when the attachment is applied, is received in a tapped opening drilled for that 90 purpose in the wall of the water jacket 12. The pipes 33 and 35 may be made of any suitable number of lengths and fittings of stock pattern in accordance with the requirements imposed by the design and location of 95 the engine.

The operation is as follows: The regular fuel tank (not shown) of the engine is filled with kerosene instead of gasoline, while a small quantity of gasoline is supplied to the tank 34. To start the engine, the needle valve 16 is closed, the needle valve 25 opened, and the two-way valve 26 turned into the position shown in Fig. 3, thereby placing the passage 27 in communication 105 with the passage 23 and closing the passage 28. Gasolene from the tank 34 will thereupon flow, through the pipe 33, to the nozzle 24, and the engine may be started in the usual manner, the only difference being that 110 the fuel is delivered by the nozzle 24 instead of by the nozzle 15. After the en-

gine has been started, and has run a sufficient length of time to generate the requisite heat in the water of the cooling system, the needle valve 16 is opened, the needle valve 25 is slightly readjusted, if necessary, and the two-way valve 26 turned into the position shown in Fig. 1, placing the passage 28 in communication with the passage 23, and closing the passage 27, thereby cutting off the supply of gasoline from the tank 34. Fuel (in this instance, however, kerosene instead of gasoline), is now drawn from the regular fuel tank and discharged through the nozzle 15 in the usual manner. At the same time hot water from the water jacket is drawn through the pipe 36 and discharged by the nozzle 24, heating and vaporizing the kerosene and mixing with the same together with air from the air intake 17, whereby explosive charges are supplied to the engine cylinder.

It will be seen that the attachment above described may, with slight trouble and expense, be applied to any existing engine of the proper type, it being only necessary to drill and tap the openings for the nipples 21 and 35 in the intake and water jacket, respectively, and to make the required pipe connections.

Having thus described my invention, I claim:

1. A kerosene attachment for water-cooled gasoline engines comprising an injector provided with means for attachment to the engine intake in communication therewith, means for supplying priming fluid to said injector, and a pipe leading to said injector and having a coupling adapted for connection with the cooling system of the engine, said fluid supplying means and pipe being arranged for alternative communication with said injector.

2. A kerosene attachment for water-cooled gasoline engines comprising an injector communicating with the engine intake, a pipe communicating with the water jacket of the engine, and an auxiliary supply for priming fluid, said attachment having provision for placing said pipe and auxiliary supply alternatively into communication with 50 said injector.

3. A kerosene attachment for water-cooled gasoline engines comprising a needle valve communicating with the engine intake, a pipe communicating with the water jacket 55 of the engine, an auxiliary gasoline tank, and a two-way valve adapted to place said pipe and tank alternatively into communication with said needle valve.

4. The combination with an engine having a water-jacketed working cylinder, a charge forming device, and an intake leading from said charge forming device to said cylinder, of an injector communicating with said inlet, a pipe leading from the water 65 jacket of said engine to said injector, and an auxiliary fuel supply, said pipe and fuel supply being arranged for alternative communication with said injector.

5. The combination with an engine having a cylinder, a water jacket provided with a tapped opening, a charge forming device, and an intake leading from said charge forming device to said cylinder, and having a tapped opening, of an injector comprising 75 a threaded, needle-valve-controlled nozzle located in the opening in said intake, a pipe leading to said injector and terminating in a threaded nipple located in the opening in said water jacket, and a fluid supply 80 tank connected with said injector.

In testimony whereof I affix my signature.

ARTHUR WARREN BRACKIN.
